UNITED STATES PATENT OFFICE.

GEORGE HENRY WHEARY, OF RACINE, WISCONSIN, ASSIGNOR TO WHEARY-BURGE TRUNK COMPANY, OF RACINE, WISCONSIN, A CORPORATION OF WISCONSIN.

TRUNK-SHOE-BOX RETAINING MEANS.

Application filed September 11, 1922. Serial No. 587,534.

To all whom it may concern:

Be it known that I, GEORGE HENRY WHEARY, a citizen of the United States, and resident of Racine, in the county of Racine 5 and State of Wisconsin, have invented new and useful Improvements in Trunk-Shoe-Box Retaining Means, of which the following is a description, reference being had to the accompanying drawings, which are a 10 part of this specification.

This invention relates to improvements in trunk shoe box retaining means.

Wardrobe trunks of the better class as now usually manufactured are provided 15 with receptacles of one kind or another for holding shoes. These receptacles are usually positioned in the lower front portion of the wardrobe section of the trunk and removably connected thereto. The wardrobe section 20 of the trunk is also usually provided with strips of wood mounted on the side portions of said section to hold the drawers of the drawer section in closed position when said sections are in closed position.

The shoe box connecting fixtures are usually mounted on these strips. As all of 25 these separate parts have to be fastened to the trunk section by rivets or screws, considerable work is involved, and furthermore, the parts as thus connected are not 30 as strong as could be desired.

It is one of the objects of the present invention to overcome the before mentioned objectionable features and provide a trunk 35 shoe box which may be easily removably attached to the metal valance forming part of the wardrobe section of the trunk.

A further object of the invention is to provide a trunk shoe box which is so constructed 40 and mounted within the trunk section that it may be easily swung to a position of convenient accessibility without detaching the box from the trunk section.

A further object of the invention is to 45 provide a trunk shoe box retaining means, which will permit the shoe box being easily disconnected from the trunk section when desired.

A further object of the invention is to 50 provide a shoe box retaining means in which the trunk valance is utilized as part of the retaining means.

A further object of the invention is to 55 provide a trunk shoe box retaining means which is of simple construction, is strong

and durable, and is well adapted for the purpose described.

With the above and other objects in view, the invention consists of the improved trunk shoe box retaining means and its parts and 60 combinations as set forth in the claims, and all equivalents thereof.

In the accompanying drawing in which the same reference characters indicate the 65 same parts in all of the views:

Fig. 1 is a front view of the lower portion of a wardrobe trunk provided with the improved trunk shoe box retaining means, the trunk sections being shown in open position;

Fig. 2 is a transverse sectional view taken on line 2—2 of Fig. 1;

Fig. 3 is a perspective view of one corner portion of the shoe box showing an improved fixture part mounted thereon; and

Fig. 4 is a sectional detail view taken on line 4—4 of Fig. 2.

Referring to the drawing, the numeral 5 indicates a portion of a wardrobe trunk, 6 the drawer section and 7 the wardrobe 80 section which is provided with the improved shoe box 8 in the lower portion thereof. The shoe box is of rectangular form and is of a length to easily fit between the opposite side front flanges 9 and the reinforcing valance metal flanges 10 forming part thereof to permit garments suspended 85 in the wardrobe section to hang in the rear of the shoe box.

In shoe boxes of this type, the cover (not 90 shown) is usually in the rear and hinged to the bottom portion of the box and extends upwardly therefrom so that it is necessary to remove or swing the box outwardly and downwardly from the wardrobe section to gain access to the contents of the box. The lower end portions of the reinforcing metal flanges 10 of the valance are

notched as indicated by the numeral 13 to permit the passage therethrough of trunnions 14 mounted on the front, lower opposite side portions of the box. The flanges 9 are recessed as at 9' to form sockets to receive said trunnions 14 and form a pivotal or hinged connection therebetween. The lower portions of the sockets 9' extend below the notches 13 so that, when the trunnions are mounted therein, they are free to turn but they cannot be removed unless the box is moved bodily upwardly 110

and then outwardly to disengage the trunnions from the recesses. This construction permits the box to be freely swung outwardly or inwardly as desired.

5 The upper opposite side and front portions of the box have mounted thereon the improved locking members 15 which comprise front portions 16, rearwardly extending arms 17 and right angular extending locking 10 arms 18 having notches or recesses in their lower edge portions to form locking shoulders 19. Rivets 15' extending through the rearward arms and the front portions fasten said members to the box. The end 15 portions 18' of said locking arms are beveled or rounded so that when the trunnions are mounted in the sockets 9' and the upper portion of the box is swung inwardly into the trunk section, the said rounded edges 20 will more easily enter the locking slots or recesses 20, formed in the valance members 10. The flanges 9 are also recessed as at 20' to receive said locking arms 18. The recessed portions of the locking arms engage 25 the lower portions of the valance flanges forming the slots 20 and lock the box against inward or outward movement, while the side portions of the flange slots and the locking arms prevent side movement of the box 30 with relation to the trunk section.

To swing the box outwardly, it is only necessary to lift the box a sufficient distance to clear the locking shoulders of the locking arms from the lower edge portions of 35 valance slots and then swing the box downwardly, and if it is desired to remove the box from the trunk, the trunnions are raised to disengage the lower valance recesses 9'.

40 When in locked position with the trunk sections swung together, the valance slots and recesses are closed by the drawer sections and the trunnions and the locking arms are locked in closed position and the 45 shoe box will be maintained firmly in position.

From the foregoing description it will be seen that the trunk shoe box retaining means is of very simple construction and is well 50 adapted for the purpose described.

What I claim as my invention is:

1. The combination with a trunk section 55 provided with a shoe box, of a means for removably securing the shoe box to the trunk section, comprising a valance member mounted on the front edge of the trunk section and extending the height of the trunk and having recesses formed in medial opposite portions thereof, a shoe box positioned between said recessed valance portions, 60 angular locking members mounted on the upper portions of the shoe box and having angular shouldered portions which extend into and lockingly engage the opposite recesses for removably holding the shoe box in 65 its inner upper position, and means for pivotally and removably connecting the lower portion of the shoe box to the valance members of the trunk.

2. The combination with a trunk section 70 provided with a shoe box, of a means for removably securing the shoe box to the trunk section, comprising a valance member mounted on the front edge of the trunk section and having vertically extending 75 elongated recess formed in opposite portions thereof, a shoe box positioned between said recessed valance portions, locking members mounted on the opposite upper front and side portions of the shoe box and having right angularly extending attaching arms and right angular inwardly extending and offset portions which enter the opposite elongated recesses and removably hold the 80 shoe box in its inner position, and means for pivotally and removably connecting the lower portion of the shoe box to the trunk.

3. A locking member for a trunk shoe 85 box, comprising a perforated attaching member having a perforated right angular extending attaching arm and a right angular extending locking arm formed with a locking shoulder on its lower edge, the locking arm being offset laterally from the attaching arm.

In testimony whereof, I affix my signature.

GEORGE HENRY WHEARY.
